TELEPHONE SYSTEM

Clarence E. Lomax, Oak Park, Ill., assignor to
 Associated Electric Laboratories, Inc., Chicago,
 Ill., a corporation of Delaware

Application July 20, 1938, Serial No. 220,162

18 Claims. (Cl. 179—18)

The present invention relates to telephone systems and more particularly to improvements in intercommunication telephone systems of the character adapted for use in conjunction with the apparatus of a regular telephone system.

In an intercommunication telephone system designed to provide more direct communication facilities between one or more master or executive telephone stations and a plurality of subordinate telephone systems, direct lines are usually provided which individually extend between the master stations and the subordinate stations. For the convenience of the subscriber in whose office a master station is located, it is desirable to provide thereat an auxiliary transmitter and an auxiliary receiver in the form of a loud speaker. The provision of such auxiliary transmitting and receiving elements gives rise to the problem of obtaining a sufficiently high level of sound output from the loud speaker and a sufficiently high sound input to the auxiliary transmitter to render a conversation being held over one of the direct lines readily understandable at each end of the line. In the past it has been the practice to solve this problem by using one or more vacuum tube amplifiers for raising the level of the signal currents transmitted from and received at the master station, thereby to insure the requisite sound output levels at each end of the connection extending to the master station. While this arrangement is perfectly satisfactory in operation, it is somewhat expensive and, accordingly, it is desirable to avoid the use of amplifiers wherever possible.

It is an object of the present invention to provide an improved telephone system of the character described wherein the circuit apparatus is arranged in an improved manner to minimize all signal energy losses in the signal current transmission channel, whereby no amplification is required for satisfactory sound reproduction when auxiliary transmitting and receiving units are provided at the master station.

It is another object of the invention to provide, in a system of the character described, an improved substation circuit which may selectively be connected to either of two lines extending to the circuit and is so arranged that the induction coil included therein is only operatively connected in the circuit when the circuit is connected to a particular one of the two lines extending thereto.

It is a further object of the invention to provide, in a system of the character described, improved circuits for signaling between the stations of the system, which circuits are so arranged that the identity of calling stations is indicated at the called stations.

The invention is illustrated as being embodied in a telephone system wherein the lines forming

the intercommunication network are provided as an adjunct to the regular substation lines and the switching apparatus of an automatic exchange by way of which connections are established between the regular substation lines in 5 the usual manner. The arrangement of the apparatus is such that the subordinate substation circuits and, more particularly, the transmitters and receivers respectively embodied there-in are used both on regular calls routed by 10 way of the automatic exchange and on calls routed by way of the subordinate or direct lines forming the intercommunication network. In the illustrated embodiment of the invention there are provided a plurality of master or executive 15 telephone stations and a plurality of subordinate telephone stations, together with lines directly extending between each of the master stations and each of the subordinate stations. In accordance with one feature of the invention, 20 each of the master stations includes signal devices individually corresponding to the subordinate stations, which signal devices form a part of means for identifying calling ones of the subordinate stations on direct calls incoming to 25 the master stations. Also, signal devices individually corresponding to the master stations are provided at each of the subordinate stations, these latter signaling devices forming a part of means for identifying calling ones of the master 30 stations on calls incoming to the subordinate stations. In accordance with a further feature of the invention, the switching apparatus which is operative to set up a direct call connection between any one of the master stations and any 35 one of the subordinate stations includes means for excluding the induction coil or coupling device from the substation circuit of the subordinate station, thereby to minimize the signal 40 energy losses involved in the connection to an extent such that an auxiliary transmitter and auxiliary receiving means of the loud speaking type may satisfactorily be used at the master station without providing any amplification in the signal current transmission channel. More 45 particularly, the lines making up the intercommunication network are provided with three conductors each, and the switching apparatus utilized in setting up a direct call connection between one of the master stations and one of 50 the subordinate stations includes a switch located at the subordinate station which is operative to couple the receiver at the subordinate station to one pair of conductors of the line extending to the master station, and also to 55 connect the transmitter at the subordinate station directly to another pair of conductors of the line extending to the master station, whereby the induction coil of the subordinate substation circuit is excluded from this circuit and 60

substantially independent channels are provided for transmitting audio frequency energy between the connected stations in the respective two directions of transmission.

5 Further features of the invention pertain to the particular arrangement of the circuit elements whereby the above and additional operating features are attained.

10 The novel features believed to be characteristic of the invention are set forth with particularity in the appended claims. The invention, both as to its organization and method of operation, together with further objects and advantages thereof, will best be understood by 15 reference to the specification taken in connection with the accompanying drawings in which Figures 1 and 2, taken together, illustrate a telephone system having embodied therein the features of the invention as briefly outlined above.

20 Referring now to the drawings, the system there illustrated comprises an automatic exchange 10 having line switching apparatus embodied therein which may be of any desired construction and arrangement, although preferably this apparatus is of the well-known Strowger step-by-step automatic type.

25 For example, the switching apparatus provided in the exchange 10 may conventionally comprise non-numerical finder switches of the Strowger type having access to the various lines of the system, impulse responsive trunk selecting selector switches individually associated with the finder switches, and impulse responsive connector switches, also of the Strowger type, accessible to the selector switches and having access to the lines of the system.

30 Extending to the exchange 10 and terminating in the bank contacts of the various finder and connector switches are a plurality of substation lines, four of which are indicated 35 at 11, 12, 13 and 14, respectively. The lines 11 and 12 individually extend to the telephone stations A and B which are of identical arrangement and are designated as being master or executive stations. The lines 13 and 14, on the 40 other hand, individually extend to the substations 15 and 16 which are also of identical arrangement and are hereinafter referred to as subordinate stations.

45 Briefly described, the apparatus provided at the master station A comprises a transmitter 17 and a receiver 18 which are preferably combined to form an instrument of the hand-set type. This instrument, when not in use, is supported upon a cradle or hook, not shown, but is removable therefrom for use. Arranged to operate in response to removal of the hand-set from its supporting element is a hook switch 19 which comprises the switch springs indicated at 20 to 50

23, inclusive. The substation apparatus provided at the station A further comprises a signal device in the form of a bell or ringer 29 bridged between the line conductors 11a and 11b of the line 11 in series with a condenser 30. This signal device is arranged to be energized in response to the 55 application of ringing voltage to the line 11 when this line is seized by one of the connector switches in the exchange 10 and is found to be idle. For the purpose of controlling the automatic switching apparatus provided in the exchange 10 on

60 regular calls outgoing from the station A, there is provided an impulsing device 24 which comprises impulsing springs 25 and shunt springs 26, 27 and 28. The transmitter 17, the receiver 18, the hook switch 19 and the impulsing device 24 are interconnected with the windings 32, 33

and 34 of an induction coil 31 to form a substation circuit of the well-known anti-side-tone type.

5 The apparatus provided at the master station A and thus far described is normally used on calls routed by way of the line 11 extending to the automatic exchange 10. There is also provided at this telephone station apparatus which is adapted to be used on calls routed by way of the lines of the intercommunication network and referred to more particularly hereinafter. This additional apparatus comprises an auxiliary transmitter 35, auxiliary receiving means in the form of a loud speaker 36 and an induction coil 49 which comprises the windings indicated at 50 to 57, inclusive. For the purpose of initiating and answering calls routed by way of the lines directly extending to the subordinate telephone stations, there are provided a plurality of key operated call and answer switches 71, 71a, etc., which individually correspond to the subordinate telephone stations. Each of the call and answer switches 71, 71a, etc., is of the locking type such that when once operated to its off-normal position it is restrained in its off-normal position until manually restored to normal. In order to identify the calls incoming to the master station A and routed by way of the lines of the intercommunication network, there are provided a plurality of visual signal devices 63, 63a, etc., which also individually correspond to the subordinate stations and are only operative on calls incoming from the respective corresponding subordinate stations. The visual signals afforded by the selective operation of the drops 63, 63a, etc., are supplemented by an audible signal which is produced by operation of a buzzer 62 commonly associated with all of the subordinate stations. For the purpose of controlling the buzzer 62 and for additional control purposes described in greater detail hereinafter, there are provided four relays R100, R110, R130 and R120, the last of which is of the slow-to-operate type and is in effect a slow acting device operative in response to operation of the relay R130. More particularly, the relay R130 is commonly included in the operating circuits for all of the drops 63, 63a, etc., and is operative to initiate the operation of the buzzer 62. The relay R120 is also operative in response to operation of the relay R130 and is arranged to arrest the operation of the buzzer 62 when it assumes its fully operated position. The two relays R100 and R110 cooperate to cause the operation of the buzzer 62 when a conversing party at the telephone station A neglects to restore an operated one of the switches 71, 71a, etc., to normal after the connection has been cleared out at the end distant from the station A. A key controlled switch comprising the contact springs 9 is provided for controlling the relay R130 in the manner described in detail hereinafter. For the purpose of transmitting ringing current by way of a selected one of the subordinate lines, there is provided a key operated ringing switch 64 which is of the non-locking type and includes contact springs 65 and 70 connected to the opposite terminals of a ringing current source, not shown.

65 As indicated above, the transmitter 17 and the receiver 18 are normally used in conjunction with calls routed by way of the regular substation line 11, and the auxiliary transmitter 35 and loud speaker 36 are normally used on calls routed by way of the lines of the intercommunica- 70 75

tion network. The arrangement is such, however, that the transmitter 17 and the receiver 18 may be used on calls of the latter character. To this end a key operated transfer switch 31 of the locking type is provided which includes contact springs appropriately arranged to permit the transmitter 17 and the receiver 18 to be substituted for the auxiliary transmitting and receiving means, respectively, in communicating over any established connection utilizing one of the lines of the intercommunication network.

In the arrangement illustrated, only four of the subordinate lines making up the intercommunication network are illustrated, which four lines are indicated at 82, 83, 84 and 85, respectively. Of the enumerated lines, the line 82 extends between the master station A and the subordinate station 15; the line 83 extends between the master station B and the subordinate station 15; the line 84 extends between the master station A and the subordinate station 16; and the line 85 extends between the master station B and the subordinate station 16.

The subordinate stations include the same apparatus arranged in the same manner and, hence, only the details of the subordinate station 15 are illustrated. In brief, the apparatus provided at this station comprises a transmitter 86, a receiver 87 and an induction coil 91 arranged to be interconnected to form a substation circuit of the well-known anti-side-tone type. The substation circuit includes one set of line terminals for each line incoming thereto. Thus, the conductors of the line 13 are connected to the line terminals 6a and 6b; the three conductors of the line 83 are connected to the line terminals 7a, 7b and 7c; and the three conductors of the line 82 extend to the line terminals 8a, 8b and 8c. The transmitter 86 and the receiver 87 are preferably combined to form an instrument of the hand-set type which is supported upon a cradle when not being used and is removed therefrom when taken for use. Arranged to be operated in response to removal of the receiver 87 from its supporting cradle is a cradle or switch hook 88 comprising contact springs 224 to 227, inclusive, shown in the closed circuited position which they assume when the receiver is removed from its supporting element. The apparatus provided at the station 15 further comprises a signal device in the form of a ringer 95a bridged between the line conductors 13a and 13b of the line 13 in series with a condenser 96a. This signal device is only operative on calls routed by way of the automatic switching equipment provided in the exchange 10 and when ringing current is projected by this apparatus over the line 13.

In order to adapt the transmitting and receiving means provided at the station 15 for use on calls routed from the master stations over the subordinate lines to the station 15, there is provided a pair of switching relays R200 and R210 which individually correspond to the master stations A and B, respectively. The relay R200 is arranged to be controlled by a key operated switch comprising the springs 97, and the relay R210 is provided with an operating circuit which is similarly arranged to be completed through operation of a key controlled switch comprising the springs 98. The two key operated switches noted are of the locking type and each thereof is operable to its off-normal position to close the contact springs embodied therein without affecting the position of the other switch. A mechanical 75 interlock indicated by the dotted line U is pro-

vided between the operating mechanism of each of the two key controlled switches and the operating mechanism of the hook or cradle switch 88. This mechanical interlock is so arranged that either of the two key controlled switches may be 5 operated to the off-normal position without affecting the position of the cradle or hook switch 88 but, when the receiver 87 is replaced upon its supporting element, any operated one of the two key controlled switches is restored to its normal 10 position. Since key controlled switches arranged partially to be controlled by an associated hook switch in the manner just described are well known in the art, the details of the mechanical arrangement are omitted in the interests of simplifying the disclosure. For the purpose of signaling the subordinate station subscriber on calls incoming to the station 15 and routed by way of the subordinate lines 82 and 83, there are provided two additional signal devices in the form of 20 ringers 95b and 95c which individually correspond to the master stations B and A, respectively. More particularly, the ringer 95b is bridged between the line conductors 83a and 83b in series with a condenser 96b, and the ringer 95c is bridged between the line conductors 82a and 82b in series with a condenser 96c. The plurality of signal devices 95a, 95b and 95c individually have distinctive 25 tone characteristics such that the produced tone occasioned by operation of any one thereof indicates the particular master station which is calling.

The manner in which calls are routed by way of the automatic switching equipment provided in the exchange 10 between the various substations of the system is, in all respects, substantially similar to the operation of any conventional automatic system. Briefly, to consider the operation of the apparatus to set up a connection between the stations A and 15 on a call initiated at the 40 master station A, it is pointed out that operation of the apparatus is initiated when the calling party removes the receiver 18 from its supporting element to cause the contact springs of the hook or cradle switch 19 to be moved to the closed circuited position illustrated in the drawings. It will be noted that with the switch 19 in this position, a direct current bridge is placed across the line conductors of the line 11 individual to the master station A. The bridging path may be 50 traced as extending by way of the conductor 11a, the springs 41, 40 and 25, the transmitter 17, the springs 44, 43, 23 and 22 and the induction coil winding 33 to the opposite line conductor 11b. When this bridging path is completed, a selected 55 one of the non-numerical finder switches provided in the exchange 10 is caused to operate to seize the calling line 11 and to switch the calling loop circuit through to an associated one of the numerical selector switches. When this operation 60 is completed, dial tone is returned over the loop to indicate to the calling party that the dialing operation may be started. During the dialing operation, the calling loop circuit is interrupted at the springs 25 of the impulsing device 24 a number of times determined by the directory number identifying the called subordinate station 15. Also, during each series of impulses, the shunt springs 26, 27 and 28 are moved to the closed circuited position to short-circuit the transmitter 17 70 and the receiver 18 in the usual manner. The seized selector switch in the exchange 10 responds to the impulses of the first digit dialed at the master station A by selecting an idle one of the group of connector switches having access to the 75

called line 13. The selector connector switch, in turn, responds to the impulses of the final two digits by selecting the called line 13 from the group of lines extending thereto. In accordance with conventional practice, the connector switches are arranged to test selected called lines to determine the idle or busy condition of the selected lines each time one of the connector switches is operated to a position corresponding to a desired called line. Thus, in the case here being considered, when the line 13 is selected by an operated one of the connector switches in the exchange 10, this switch operates to determine the idle or busy condition of the line 13. If the line is busy at the time it is selected, busy tone current is returned over the calling loop circuit and the resulting operation of the receiver 18 indicates to the calling party that the desired connection cannot immediately be obtained. On the other hand, if the called line is idle at the time it is selected, ringing current is projected over the line 13 to energize the signal device 95, and ring-back-tone current is projected back over the calling loop circuit to indicate to the calling party that the ringing operation is being performed.

The desired conversational connection is completed when the call is answered at the subordinate station 15. More particularly, when the answering party removes the hand-set comprising the receiver 87 from its supporting cradle, the switch 88 is operated to its off-normal position so that the springs 224 to 227, inclusive, assume the closed circuited positions indicated in the drawing. It will be noted that, with the switch 88 occupying its off-normal position, a direct current bridge is placed across the line conductors 13_a and 13_b of the line 13. This bridging path may partially be traced as extending by way of the conductor 13_a, RC212, RA211, RC202, RA201, the impulsive springs 223, the transmitter 86, RA214, RC215, RA204, RC206, the springs 221 and 226, and the induction coil winding 93 to the opposite line conductor 13_b. When this bridging path is completed, certain of the control apparatus embodied in the selected connector switch in the exchange 10 is caused to operate to arrest the ringing operation and to reverse battery back over the calling loop circuit to the calling station A. The manner in which the release of the established connection is achieved depends upon the character and arrangement of the automatic switching equipment provided in the exchange 10. For example, this equipment may be so arranged that the release of the operated switch train is only effected when the connection is cleared out at both ends thereof. Alternatively, the switching equipment may be so arranged that the release of the connection is under the control of the calling party. In any case, the operated switch train is released when the calling and called parties hang up to interrupt the respective bridging paths traced previously. Obviously, when the handsets respectively provided at the stations A and 15 are replaced upon their respective supporting cradles, the two hook or cradle switches 19 and 88 are respectively returned to their normal positions and the substation apparatus located at each of the two stations A and 15 is returned to normal.

70 The manner in which a connection is routed from the subordinate station 15 by way of the automatic switching equipment, provided in the exchange 10, to the master station A, is substantially similar to the operation of the apparatus as described above. In this case, the impulsive de-

vice 89 is utilized to transmit the switch control impulses to the automatic switching equipment provided in the exchange 10, and the signal device 29 provided at the station A is energized during the ringing operation. Aside from these two differences the connection is completed and released in the manner described above with reference to the call initiated at the station A.

From the foregoing description it will be apparent that on any call routed by way of the automatic exchange 10 to or from the subordinate station 15, the windings of the induction coil 91 are operatively included in the substation circuit provided at the station 15. The purpose of including this induction coil is to eliminate the side tone in the usual manner. The induction coil 91 is incidentally effective to absorb a portion of the voice frequency energy transmitted to and from the subordinate station. When the usual type of receiver is being used at each end of the connection, this absorption of energy is of no importance since the level of signal energy transmitted from the station 15 to the other end of the connection is amply sufficient when the sound is being transmitted to the ear of a listener through a receiver held closely adjacent the listener's ear. When, however, a reproducing device of the loud speaking type is utilized at the distant end of the connection, the loss of energy occasioned by the inclusion of the induction coil 91 in the substation circuit of the station 15, or another similar station, is objectionable since it tends to lower the level of the sound output of the loud speaker. To obviate this difficulty there is provided at each of the subordinate stations means comprising the switching relays R200 and R210 for excluding the induction coil 91 from the substation circuit on calls routed by way of the subordinate lines making up the intercommunication network.

Referring now more particularly to the operation of the apparatus on a call initiated at the subordinate station 15 and routed by way of the line 82 to the master station A, it is pointed out that to initiate the call the calling party first operates the key controlled switch comprising the springs 97 to the off-normal position, thereby to complete an obvious circuit for energizing the relay R200. Upon operating, the relay R200 disconnects the substation apparatus from the line 13 and operatively associates this apparatus with the conductors of the line 82 extending to the master station A. More particularly, at RA201 and RA204 and their respective associated contacts RC203 and RC205, the relay R200 connects the transmitter 86 across the line conductors 82_a and 82_b. At RA204 and RA207 and their respective associated contacts RC205 and RC208, the relay R200 prepares a path for connecting the receiver 87 across the line conductors 82_b and 82_c. Following operation of the switch comprising the springs 97 to the off-normal position to cause the operation of R200, the calling party removes the handset from its supporting cradle, thereby to cause the switch 88 to be operated to its off-normal position. At the springs 224, the receiver 87 is connected across the line conductors 82_a and 82_c when the switch 88 operates.

When the relay R200 operates, it completes a bridging path between the line conductors 82_a and 82_b, thus energizing the drop 63 in series with the relay R130, both provided at the master station A. More particularly, the two last-mentioned elements are energized over a circuit extending from ground at the spring 76 by way of the spring 75, the line conductor 82_a, RC203, 75

RA201, the impulsive springs 223, the transmitter 82, RA214, RC215, RA204, RC205, the line conductor 82b, the springs 78 and 77, the winding of the drop 63 and the winding of R130 to battery. When energized over this circuit, the drop 63 operates to give a visual indication that a call originating at the subordinate station 15 awaits attention. The relay R130 also operates when energized over the circuit just traced and, upon operating, completes at RA131 a circuit extending by way of RA121 for energizing the buzzer 62. The resulting operation of the buzzer 62 informs the subscriber at the master station A that an incoming call awaits attention, and by observing the operated condition of the drop 63 the called subscriber is informed that the subordinate station 15 is the calling station. With the switch springs 9 in the closed circuited position shown, operation of the signal device 62 is of limited duration since, upon operating, the relay R130 completes, at RA131, a circuit extending by way of the springs 9 for energizing the slow-to-operate relay R120. The last-mentioned relay operates after an interval to open at RA121 a point in the above-traced circuit for energizing the signal device 62, thereby to arrest the operation of this device.

The party who answers the call has the option of using the hand-set comprising the transmitter 17 and the receiver 18 or the auxiliary transmitter 35 and the auxiliary receiving means 36 in communicating over the connection. Assuming that the transmitter 35 and the receiver 36 are to be used, the call is answered by operating the call and answer switch 71, corresponding to the station 15, to the off-normal position. When the switch 71 is operated to its off-normal position, two points are opened in the above-traced circuit for energizing the winding of the drop 63 in series with the relay R130, and a circuit is completed for energizing the relay R100 in series with the transmitter 86 provided at the calling station 15. Upon restoring, the relay R130 opens, at RA131, a further point in the circuit for energizing the buzzer 62 and a point in the operating circuit for R120, causing the last-mentioned relay to restore. The circuit for energizing R100 and the transmitter 15 extends from ground at the upper terminal of the winding 57 by way of this winding, the springs 67, 66, 74 and 75, the line conductor 82a, RC203, RA201, the impulsive springs 223, the transmitter 86, RA214, RC215, RA204, RC205, the line conductor 82b, the springs 78, 79, 69 and 68, the winding 56 and the winding of R100 to battery. When energized over this circuit, the relay R100 operates to interrupt at RA101 and RC102 a point in the operating circuit, traced herein-after, for R110. It will be noted that talking battery voltage is impressed across the terminals of the transmitter 86 over the circuit just traced and by way of which R100 is energized. It will further be noted that the windings of the induction coil 91 are excluded from this circuit. At RA101 and RC103, the relay R100, upon operating, completes a circuit for impressing talking battery voltage across the terminals of the transmitter 35. More particularly, the transmitter 35 is energized over a circuit extending from ground at RA101 by way of RC103, the winding 51, the transmitter 35, the springs 38 and 39, the winding 50 and the resistor 50' to battery. Following the operation of the switch 71 to its off-normal position, the desired communication

connection is fully established. This connection comprises two substantially independent channels for transmitting audio frequency energy in the respective two directions of transmission. More particularly, voice frequency currents developed by operation of the transmitter 35 circulate in the closed circuit comprising this transmitter 35, the winding 51, the condenser 59, the winding 50 and the switch springs 39 and 38. By virtue of the alternating character of these currents, corresponding induced voltages are developed in the coupled windings 54 and 55 of the induction coil 49. These induced voltages cause corresponding currents to flow through the receiver 81 provided at the subordinate station 15, the closed circuit traversed by these currents extending from the lower terminal of the winding 55 by way of the springs 68, 69, 79 and 78, the line conductor 82b, RC205, RA204, RC215, RA214, the receiver 87, the springs 224, 20 RA201, RC208, the line conductor 82c, the springs 81 and 80, the winding 54, the condenser 58 and the winding 55 back to the lower terminal of the last-named winding. The circuits just described constitute the channel for transmitting energy developed by operation of the transmitter 35 to the receiver 87. Voice frequency currents developed by operation of the transmitter 86 traverse a circuit which may be traced as extending from the lower terminal of the transmitter 86 by way of RA214, RC215, RA204, RC205, the line conductor 82b, the switch springs 78, 79, 69 and 68, the winding 56, the condenser 61, the winding 57, the switch springs 67, 66, 74 and 75, the line conductor 82a, RC203, RA201 35 and the impulsive springs 223 to the upper terminal of the transmitter 86. Due to the alternating character of these currents, corresponding induced voltages are developed in the windings 52 and 53 coupled respectively to the 40 windings 56 and 57. These induced voltages cause corresponding currents to traverse the closed circuit which comprises the windings 52 and 53, the condenser 60, the switch springs 41 and 48 and the voice coil of the loud speaker 45 36. The circuits just described constitute the other channel, namely, that for transmitting voice frequency energy from the subordinate station 15 to the master station A. It will be noted that the two channels have commonly 50 included therein the line conductor 82b. The resistance of this conductor, however, is insufficient to provide any substantial coupling between the two channels. Also, the induction coil 49 is so arranged that the windings 52, 53, 55 55 and 57 are well shielded from the windings 50, 51, 54 and 55 so that no substantial coupling exists between the two sets of windings. Hence "singing" of the network is reduced to a minimum. 60

The key operated switch comprising the springs 9 is provided for the purpose of opening a point in the operating circuit for the slow-to-operate relay R120, whereby the buzzer 62 is caused continuously to operate when a call is extended 65 by way of one of the subordinate lines to the master station A and until the call is answered. Thus, in the case considered above, if the key operated switch comprising the springs 9 occupies its off-normal position, such that the springs 70 9 are open at the time the relay R130 operates, the operating circuit for R120 is not completed in response to operation of the relay R130 and, hence, the buzzer 62 is continuously energized over the circuit extending from ground at RA131 75

until the call is answered at the master station A. When the call and answer switch 71 is operated to its off-normal position to answer the call, the operating circuit for R130 is interrupted and the last-mentioned relay restores to open, at RA131, the operating circuit for the buzzer 62, thereby to terminate the signal. Thus, it will be seen that by providing the key controlled switch comprising the springs 9, the subscriber at the master station A has the option of arranging the circuit so that the buzzer 62 is energized for a limited time interval or is continuously energized on calls routed by way of the subordinate lines to his substation.

15 As indicated previously, the hand-set comprising the transmitter 17 and the receiver 18 may be used in lieu of the transmitter 35 and the loud speaker 36 in communicating over the connection just described. In order operatively to include the transmitter 17 and the receiver 18 in the substation circuit of the station A, the transfer switch 37 is operated to its off-normal position. Operation of this switch to its off-normal position effects a direct substitution of the transmitter 17 for the transmitter 35 and of the receiver 18 for the loud speaker 36 in the substation circuit. Thus, at the springs 43 and 46 and their respective associated springs 42 and 48, the receiver 18 is substituted for the loud speaker 36 in the substation circuit. At the springs 43 and 40 and their respective associated contacts 42 and 38 the transmitter 17 is likewise substituted for the transmitter 35 in the substation circuit. Obviously, by operating the transfer switch 37 between its two operating positions, the hand-set may be substituted for the auxiliary transmitting and receiving means at will and as many times as desired during a single conversation. By providing this feature, it is possible for the subscriber at the station A to use the regular hand-set when he desires to carry on a semi-private conversation with a party located at one of the subordinate stations.

In order to release the connection as established in the manner set forth above, the switch 71 is returned to its normal position and the hand-set comprising the transmitter 86 and the receiver 87 is replaced upon its supporting cradle. Also, if the hand-set comprising the transmitter 50 17 and the receiver 18 is being used at the station A, this hand-set is replaced upon its supporting cradle and the transfer switch 37 is returned to its normal position. When the switch 71 is restored to its normal position, the two voice frequency energy transmission channels described above are interrupted and the operating circuit for the relay R100 is opened, thus completely breaking the connection. When the hand-set comprising the transmitter 17 and the receiver 60 18 is replaced upon its supporting cradle, the hook switch 19 is returned to its normal position and, thus, the apparatus provided at the station A is completely restored to normal. When the calling party at the station 15 replaces the hand-set upon its supporting cradle, the cradle switch 88 is restored to normal and, through operation of the mechanical interlock U, the key controlled switch comprising the springs 97 is also restored to its normal position. When the last-mentioned 70 switch is restored to normal, the springs 97 are opened to interrupt the operating circuit for R200, causing this relay to restore to reconnect the substation circuit for use in communicating over the line 18.

75 As pointed out previously, provisions are made

for signaling the subscriber at the station A in the event he neglects to restore an operated one of the call and answer switches to normal after a conversation has been terminated and the connection cleared out at the subordinate station. Thus, in the case just described, if the answering party in the station A neglects to restore the switch 71 to normal, a circuit is completed for energizing the buzzer 62 when the connection is cleared out at the station 15. More particularly, when the hand-set provided at the station 15 is replaced upon its supporting cradle to cause the restoration of R200, the loop circuit over which R100 is being held energized is interrupted at RA201 and RA204 and their respective associated contacts RC203 and RC205. Upon restoring, the relay R100 completes at RA101 a circuit for energizing R110, this circuit extending from ground at RA101 by way of RC102, the switch springs 13 and 12 and the winding of R110 to 20 battery. Upon operating, the relay R110 completes at RA112, an obvious alternative circuit for energizing the buzzer 62, and the resulting operation of the buzzer gives an audible indication that the switch 71 should be returned to its normal position. When the switch 71 is thereafter restored to normal the operating circuit for R110, as traced above, is interrupted at the springs 12 and 13, causing this relay to restore to open at RA112 the operating circuit for the 30 buzzer 62, thereby to terminate the signal.

In the event the call initiated at the subordinate station 15 is intended for the master station B rather than the master station A, the key operated switch comprising the springs 98 is operated by the calling party rather than the key operated switch comprising the springs 97. When the springs 98 are closed the relay R210 operates to connect the sub-station apparatus provided at the station 15 to the line 83 extending to the master station B. Thus, at RA211 and RA214 and their respective associated contacts RC213 and RC216, the relay R210, upon operating, connects the transmitter 86 across the line conductors 83a and 83b. Similarly, at RA214 and RA217 and their respective associated contacts RC216 and RC218, the relay R210 prepares a path for connecting the receiver 87 across the line conductors 83b and 83c of the line 83 extending to the master station B, which path is completed at the springs 224 of the switch 88 when the hand-set comprising the receiver 87 is removed from its supporting cradle. Aside from the fact that the switch comprising the springs 98 and the relay R210 are operated, rather than the switch comprising the springs 97 and the relay R200, the mode of operation of the apparatus to establish a communication connection between the stations 15 and B is identical with that described above with reference to the connection set up between the stations 15 and A.

Referring now more particularly to the operation of the apparatus to establish a connection including the line 82 and extending between the stations A and 15 on a call initiated at the station A, it is pointed out that to initiate the call the switch 71 corresponding to the station 15 is first operated to its off-normal position, at which time the above-traced circuit is completed for energizing R110. Upon operating, the relay R110 completes, at RA112, the above-described circuit for energizing the buzzer 62, but the resulting operation of the buzzer is without effect since the calling party is aware that its operation results from the initiation of the call. At RA111, 75

the relay R110, upon operating, applies ground to the ringing apparatus start conductor 111', thereby to initiate the operation of this apparatus in the usual manner. Following operation 5 of the switch 71 the ringing switch 64 is operated to its off-normal position one or more times to cause ringing current to be projected over the line 82 to the subordinate station 15. More particularly, when the ringing key 64 is operated 10 to its off-normal position, the signal device 95c is energized over a circuit extending from one terminal of the ringing current source, not shown, by way of the springs 65, 66, 74 and 75, the line conductor 82a, the condenser 96a, the 15 windings of the signal device 95a, the line conductor 82b and the springs 78, 79, 69 and 70 to the opposite terminal of the ringing current source. The resulting operation of the signal device 95c indicates to the subscriber at the station 15 that his substation is being called from the master station A. To answer the call, the subscriber at the subordinate station 15 first operates the key controlled switch comprising the springs 97 to its off-normal position and then 20 moves the hand-set comprising the receiver 87 from its supporting cradle to cause the switch 88 to operate to its off-normal position. At the springs 97 the above-traced operating circuit for R200 is completed. Upon operating, the relay 25 30 R200 connects the transmitter 86 across the line conductors 82a and 82b, and the receiver 87 across the line conductors 82b and 82c, all in the manner described previously. When the transmitter 86 is connected across the line conductors 82a 35 and 82b, the above-traced circuit is completed for energizing the relay R100 which relay, upon operating, interrupts at RA101 and RC102, the previously traced operating circuit for R110. Upon restoring, the relay R110 removes, at 40 RA111, ground from the ringing apparatus start conductor 111' and opens, at RA112, the alternative operating circuit for the buzzer 62. With the cradle switch 88 and the relay R200 operated, the desired communication connection is fully established between the calling and called stations. 45 This communication connection comprises the two substantially independent energy transmission channels described previously for transmitting voice frequency currents in the respective two directions of transmission. The manner in 50 which the connection is released is the same as described previously and, hence, need not be repeated.

If a call intended for the subordinate station 55 15 is initiated at the master station B, the manner in which the apparatus functions to set up the desired connection is in all respects similar to the operation of the apparatus to establish a connection between the master station A and the subordinate station 15, it being pointed out, however, that when ringing current is projected 60 over the line 83 to the subordinate station 15 the signal device 95b is energized rather than the signal devices 95a and 95c. Due to the distinctive tone of each of the three devices noted, the subscriber at the subordinate station 15 is able 65 to discriminate between the signals and to ascertain from the particular tone produced by operation of any one of the signal devices the particular type of call, and also, which of the key 70 controlled switches should be operated to answer the call. In a similar manner the subscriber located at the master station A is informed by the selective operation of the signal devices 63, 63a, 75 etc., as to which of the call and answer keys

71, 71a, etc., should be operated to answer a call incoming to the station A.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. In a telephone system, an exchange including line switching apparatus, a first telephone station including a transmitter, a receiver and an audio frequency current coupling device arranged to be interconnected to form a substation 15 circuit, a second telephone station, means comprising said line switching apparatus for setting up a connection between said stations which includes said substation circuit, switching means operative to exclude said coupling device from 20 said substation circuit, a line extending between said stations, and means comprising said line and said switching means for setting up an alternative connection between said stations which includes said substation circuit with said coupling 25 device excluded therefrom.

2. In a telephone system, an exchange including line switching apparatus, a first telephone station including a transmitter, a receiver and an induction coil arranged to be interconnected 30 to form a substation circuit, a second telephone station, means comprising said line switching apparatus for setting up a connection between said stations which includes said substation circuit, switching means operative to exclude said induction coil from 35 said substation circuit, a line extending between said stations, and means comprising said line and said switching means for setting up an alternative connection between said stations which includes said substation circuit 40 with said induction coil excluded therefrom.

3. In a telephone system, an exchange including line switching apparatus, a first telephone station including a transmitter, a receiver and an induction coil arranged to be interconnected 45 to form a substation circuit, a second telephone station, means comprising said line switching apparatus for setting up a connection between said stations which includes said substation circuit, switching means operative to exclude said induction coil from 50 said substation circuit, a multi-conductor line extending between said stations, and means comprising said line and said switching means for setting up an alternative connection between said stations which includes 55 separate and substantially independent channels for transmitting audio frequency energy between said stations in the respective two directions of transmission, said alternative connection including said substation circuit with said induction coil excluded therefrom.

4. In a telephone system, an exchange including line switching apparatus, a first telephone station including a transmitter, a receiver and an induction coil arranged to be interconnected 65 to form a substation circuit, a second telephone station, means comprising said line switching apparatus for setting up a connection between said stations which includes said substation circuit, switching means operative to exclude said induction coil from 70 said substation circuit, a multi-conductor line extending between said stations, and means comprising said line and said switching means for setting up an alternative connection between said stations, said switching means 75

- comprising a switch provided at said first station and operative to couple said receiver to one pair of the conductors of said line and to connect said transmitter directly to another pair of the conductors of said line, whereby said induction coil is excluded from said circuit and substantially independent channels are provided for transmitting audio frequency energy between said stations in the respective two directions of transmission.
5. In a telephone system, an exchange including line switching apparatus, a first telephone station including a transmitter, a receiver and an induction coil arranged to be interconnected to form a substation circuit, a second telephone station, means comprising said line switching apparatus for setting up a connection between said stations which includes said substation circuit, switching means operative to exclude said induction coil from said substation circuit, a line extending between said stations and comprising a common conductor and two additional conductors, and means comprising said line and said switching means for setting up an alternative connection between said stations, said switching means comprising a switch located at said first station and operative to couple said receiver to said common conductor and one of said additional conductors and to connect said transmitter directly to said common conductor and the other of said additional conductors, whereby said induction coil is excluded from said circuit and substantially independent channels are provided for transmitting audio frequency energy between said stations in the respective two directions of transmission.
6. In a telephone system, an exchange including line switching apparatus, a first telephone station including a transmitter, a receiver, and an induction coil arranged to be interconnected to form a substation circuit, a second telephone station, means comprising said line switching apparatus for setting up a connection between said stations which includes said substation circuit, switching means operative to exclude said induction coil from said substation circuit, a line extending between said stations and comprising a common conductor and two additional conductors, and means comprising said line and said switching means for setting up an alternative connection between said stations, said switching means comprising a switch located at said first station and operative to couple said receiver to said common conductor and one of said additional conductors and to connect said transmitter directly to said common conductor and the other of said additional conductors, whereby said induction coil is excluded from said circuit and substantially independent channels are provided for transmitting audio frequency energy between said stations in the respective two directions of transmission, said switching means further comprising a second switch located at said second station and operative to impress talking battery voltage between said common conductor and the other of said additional conductors, thereby to energize said transmitter.
7. A telephone station including a transmitter, a receiver and an induction coil arranged to be interconnected to form a substation circuit, said circuit including two sets of line terminals adapted to be connected to two different lines extending to said station, means operative to connect said transmitter and receiver for use in communication over the line extending to one
8. A telephone station including a transmitter, a receiver and an induction coil arranged to be interconnected to form a substation circuit, said circuit including a pair of line terminals adapted to be connected to the conductors of a two conductor line extending to said station, said circuit also including a set of three line terminals adapted to be connected to the conductors of a three conductor line extending to said station, means operative to arrange said circuit for use in communicating over the line extending to said pair of terminals, and means operative to connect said transmitter for use in communicating over a pair of the conductors of said three conductor line and to connect said receiver for use in communicating over a different pair of the conductors of said three conductor line.
9. A telephone station including a transmitter, a receiver and an induction coil arranged to be interconnected to form a substation circuit, said circuit including a pair of line terminals adapted to be connected to the conductors of a two conductor line extending to said station, said circuit also including a set of three line terminals adapted to be connected to the conductors of a three conductor line extending to said station, means operative to arrange said circuit for use in communicating over the line extending to said pair of terminals, and means operative to connect said transmitter for use in communicating over a pair of the conductors of said three conductor line and to connect said receiver for use in communicating over a different pair of the conductors of said three conductor line, said last-named means including switching means for excluding said induction coil from said circuit.
10. A telephone station including a transmitter, a receiver and an induction coil arranged to be interconnected to form a substation circuit, said circuit including a pair of line terminals adapted to be connected to the conductors of a two conductor line extending to said station, said circuit also including a set of three line terminals adapted to be connected to the conductors of a three conductor line extending to said station, means operative to arrange said circuit for use in communicating over the line extending to said pair of terminals, and means operative to connect said transmitter for use in communicating over a pair of the conductors of said three conductor line and to connect said receiver for use in communicating over a different pair of the conductors of said three conductor line, said last-named means including switching means for excluding said induction coil from said circuit.
11. A telephone station including a transmitter, a receiver and an induction coil arranged to be interconnected to form a substation circuit, said circuit including two sets of line terminals adapted to be connected to two different lines, a supporting element for said receiver, means operative in response to removal of said receiver from said supporting element for connecting said transmitter and receiver for use in communicating over the line extending to one of said two sets of terminals, and means operative to connect said transmitter and receiver for use in communicating over the line extending to the other set of terminals and for excluding said induction coil from said circuit.
12. A telephone station including a transmitter,

- a receiver and an induction coil arranged to be interconnected to form a substation circuit, said circuit including two sets of line terminals adapted to be connected to two different lines, a supporting element for said receiver, means operative in response to removal of said receiver from said supporting element for arranging said circuit for use in communicating over the line extending to one of said two sets of terminals, a manually operable switch having a normal position and operable to an off-normal position, means operative in response to operation of said switch to said off-normal position for arranging said circuit for use in communicating over the line extending to the other set of terminals and for excluding said induction coil from said circuit, and means operative in response to replacement of said receiver on its supporting element for restoring said switch to its normal position.
13. A telephone station including a transmitter, a receiver and an induction coil arranged to be interconnected to form a substation circuit, said circuit including a pair of line terminals adapted to be connected to the conductors of a two conductor line extending to said station, said circuit also including a set of three line terminals adapted to be connected to the conductors of a three conductor line, a supporting element for said receiver, means operative in response to removal of said receiver from said supporting means for arranging said circuit for use in communicating over said two conductor line, and means operative to connect said transmitter for use in communicating over a pair of the conductors of said three conductor line and to connect said receiver for use in communicating over a different pair of the conductors of said three conductor line, said last-named means including switching means for excluding said induction coil from said circuit.
14. A telephone station including a transmitter, a receiver and an induction coil arranged to be interconnected to form a substation circuit, said circuit including a pair of line terminals adapted to be connected to the conductors of a two conductor line extending to said station, said circuit also including a set of three line terminals adapted to be connected to the conductors of a three conductor line, a supporting element for said receiver, means operative in response to removal of said receiver from said supporting means for arranging said circuit for use in communicating over said two conductor line, a manually operable switch having a normal position and operable to an off-normal position, means operative in response to operation of said switch for connecting said transmitter for use in communicating over a pair of the conductors of said three conductor line and for connecting said receiver for use in communicating over a different pair of the conductors of said three conductor line, means also operative in response to operation of said switch to said off-normal position for excluding said induction coil from said circuit, and means operative in response to replacement of said receiver on its supporting element for restoring said switch to normal.
15. In a telephone system, a plurality of master telephone stations, a plurality of subordinate telephone stations, lines extending between each of said master stations and each of said subordinate stations, means including said lines for setting up connections between said master stations and said subordinate stations, each of said master stations including signal devices individually corresponding to said subordinate stations and arranged to be energized by way of the associated ones of said lines, means including said signal devices for identifying calling ones of said subordinate stations on calls incoming to the master stations, each of said subordinate stations including signal devices individually corresponding to said master stations and arranged to be energized by way of the lines extending to the corresponding master stations, and means including said last-named signal devices for identifying calling ones of said master stations on calls incoming to said subordinate stations.
16. In a telephone system, a first telephone station, a plurality of telephone stations, lines extending from said first station to each of said additional stations, visual signal devices at said first station individually corresponding to said additional stations, a relay including a winding, each of said signal devices having an operating circuit, said operating circuits commonly including said winding, whereby said relay is energized and operates when any one of said circuits is completed; each of said additional stations including a receiver and a manually operable switch; means individually provided at said additional stations and individually operative in response to operation of the corresponding switches for completing the operating circuits for the corresponding ones of said signal devices, and means operative in response to operation of said relay for giving an audible signal that said first station is being called.
17. In a telephone system, a first telephone station, a plurality of telephone stations, lines extending from said first station to each of said additional stations, visual signal devices at said first station individually corresponding to said additional stations, a relay including a winding, each of said signal devices having an operating circuit, said operating circuits commonly including said winding, whereby said relay is energized and operates when any one of said circuits is completed; each of said additional stations including a receiver and a manually operable switch; means individually provided at said additional stations and individually operative in response to operation of the corresponding switches for completing the operating circuits for the corresponding ones of said signal devices, means operative in response to operation of said relay for giving an audible signal that said first station is being called, and a slow-acting control device operative in response to operation of said relay to terminate said audible signal.
18. In a telephone system, a first telephone station, a second telephone station, a line extending between said stations, a signal device at said first telephone station, an operating circuit for said signal device; said second station including a transmitter, a receiver, a receiver supporting element and a manually operable switch; means controlled by operation of said switch and removal of said receiver from its supporting element for completing said operating circuit and for connecting said transmitter and receiver for use in communicating over said line, a switch at said first station, and means including said last-named switch for impressing talking battery voltage on said line, thereby to energize said transmitter only when said last-named switch is operated.

CLARENCE E. LOMAX.
